Frederick C. Fischer

UNITED STATES PATENT OFFICE.

FRANZ A. FULLER, OF NEWARK, NEW JERSEY, ASSIGNOR TO THE J. E. MERGOTT COMPANY, OF NEWARK, NEW JERSEY, A CORPORATION OF DELAWARE.

BAG FASTENER.

1,408,728.

Specification of Letters Patent. Patented Mar. 7, 1922.

Application filed April 13, 1921. Serial No. 461,005.

To all whom it may concern:

Be it known that I, FRANZ A. FULLER, a citizen of the United States, residing in Newark, county of Essex and State of New Jersey, have invented certain new and useful Improvements in Bag Fasteners, of which the following is a specification.

The main object of this invention is to provide a spring actuated clasp of unique 10 design adapted to securely confine the hinged frame elements of a bag in intimate relation.

Another purpose is in the provision of a clasp comprised of a single unitary element 15 provided with integral means for engaging one of the frame members in a permanent but pivotal manner, the clasp, which is of unusually neat appearance, automatically engaging the other frame member upon closing 20 the bag and holding it closed until manually released.

These and other like objects, such as the avoidance of unsightly projections, lightness in weight, cheapness of construction 25 and ease of operation, are attained by the novel design, construction and arrangement of parts, hereinafter described and shown in the annexed drawings, forming an essential part of this disclosure and in which:—

30 Figure 1 is a fragmentary plan view of a conventional type of bag, showing the frame partially open and illustrating the application of the invention.

Figure 2 is an enlarged bottom plan view 35 of the clasp in detail.

Figure 3 is an end view of the same.

Figure 4 is a fragmentary plan view of the bag frame member to which the clasp is permanently attached.

40 Figure 5 is a fragmentary bottom plan view of the same, showing the clasp engaged therewith.

Figure 6 is a greatly enlarged transverse sectional view, showing the clasp in operative 45 position, the section being taken substantially on line 6—6 of Figure 1.

Stated briefly in general terms, the invention comprises a low hollow elongated clasp body, hingedly united to one of the frame 50 members and having an overhanging portion, bevelled on its under surface to engage

and snap over one or more lugs integral with the mating member of the frame, the clasp being urged into normal engaging position by a single torsion spring housed within its 55 body and fixed at one end in the frame element.

Referring now more specifically to the drawings, the numeral 10 designates the flexible walls of a conventional type of hand 60 bag, made of leather or textile fabric, such as commonly carried by women for holding miscellaneous small articles.

The bag is provided with a metal frame comprised of two members respectively 11 65 and 12, which, when open on the connecting hinges 14 present an oblong rectangle through which access to the interior of the bag may be had.

The frame member 11 is slightly larger 70 than its mate 12 so as to partially overlie it when closed.

The member 11 is also differently formed, consisting of a slightly curved outer wall, blending into a flanged top portion 15 at a 75 right angle, its outer edge being re-entrantly turned presenting a double thickness which extends to the inner straight flat wall 16, coincident with but spaced from, the outer right angled wall 11, the recess 17 between 80 the walls being receptive of the bag material.

The opposite or mating member 12 is substantially U shaped in cross section, the inner wall 18 being flattened to make contact 85 with the wall 16, while the curved portion 19, joining the inner and outer walls, is adapted to neatly fit below the flange 15 when the bag is closed, the space 20 between the walls containing the edge of the bag material.

A pull ring or knob is preferably secured to the frame element 22 in order to conveniently open or otherwise manipulate the same.

95 While the foregoing is descriptive of a preferred form of frame, it is to be understood that any similar type of bag frame may be used in connection with the clasp.

The clasp, which is positioned midway in 100 the length of the frame, comprises an elongated rectangular metal plate 24, curved

slightly lengthwise, bent downward at the back, forming a rear wall 25 and curved at the front 26, the curved portion blending into a downwardly slanting catch element 5 27 the inner edge of which extends normally over the frame member 12 when closed.

The clasp element 24 is also bent downwardly at its ends 28 and formed on the rear edges, adjacent the back 25 are prongs 10 29 adapted to pass through openings 30 formed in the frame element 11, and loosely clenched below the top wall, in the recess 17, as shown in Figures 5 and 6.

The front corners of the clasp plate 24 are 15 neatly curved as at 31 and all edges are smoothly finished.

Formed with the rear edges of the element 27 are a pair of spaced stop extensions 32 reaching rearwardly nearly to the wall 20 16 and being disposed in indented recesses formed in the frame flange 15, the purpose of these stops being to limit the distance that the clasp can be raised above the level of the element 15, when the clasp is moved 25 upward on the prongs 29 which act in a limited manner as hinges.

The clasp is normally urged tightly against the surface of the frame element 15 by a torsional spring 34 made from a single 30 strand of wire, disposed in the inner corner of the clasp elements 24 and 25 and fixedly held therein by clips 35 extending integrally from the lower edge of the clasp element 25, the clips being bent as best shown in Figure 6.

One end of the wire 34 is turned to the front, under the plate 24, as at 36, its terminal 37 being bent parallel to the main portion and disposed between the clasp elements 40 24 and 27.

The opposite end 38 of the wire is extended downwardly and passed through a small circular opening 39 formed in the frame element 15 adjacent one of the hinge 45 receiving openings 30, the wire being so bent as to press the clasp into operative position and cause the inner edge of the element 27 to engage over a pair of lugs 40 formed by shearing and pressing the metal 50 up from the highest central portion of the curved element 19 of the frame element 12.

In operation, the parts having been assembled as indicated, and the bag frame in an open position, the hinged members are 55 pressed together, the bevelled adjacent surfaces of the lugs 40 making contact with the correspondingly slanted surface of the clasp element 27, causing it to rise, overcoming the torsional effect of the spring 34, until 60 the lugs have passed the edge of the catch element 27, whereupon it snaps downward over the lugs and maintains the frame elements securely in close relation.

When it is desired to release the bag, the 65 pull 21, may be grasped in one hand, or any

other convenient part of the frame member 12, and the other hand used to grasp and raise the clasp, the projecting curved portion 26 of which is well adapted for that purpose.

While certain preferred embodiments of this device have been shown and described it will be understood that changes in the form, arrangement, proportions, sizes and details thereof may be made without departing from the scope of the invention as defined in the appended claims.

Having thus described my invention, what I desire to secure by Letters Patent and claims, is:—

1. In a bag fastener, the combination with a pair of frame members, of a clasp hinged to one of said members, means limiting the movement of said clasp, means impelling said clasp to its seat on said member, and means on the other of said members engageable with said clasp.

2. In a bag fastener, the combination with a pair of frame members, of a clasp hinged to one of said members, a torsion spring in said clasp and fixed in said member, one or more bevelled lugs formed with the other of said members, and means integral with said clasp for engaging said lugs when said frame members are closed.

3. In a bag fastener, the combination with a pair of frame members, of a plate having angularly turned rear and side edges, projections on the rear edge engaging one of said frame members in the manner of a hinge, said plate having a curved extending front, a catch element formed therewith inclining downwardly and toward the rear, means integral with the other of said frame members adapted to be engaged by said catch element, and means co-operative with said first frame member and said clasp plate adapted to cause such engagement.

4. A bag fastener comprising, in combination with a frame, a hollow clasp open partially at its bottom, means integrally formed therewith for hingedly engaging said clasp with one of the frame members, a torsional spring in said clasp adapted to normally press said clasp into operative position, means limiting the rotative movement of said clasp, and means integral with the other of said frame members engageable with the bottom wall of said clasp.

5. A bag fastener comprising, in combination with a frame, a hollow clasp open partially at its bottom, means integrally formed therewith for hingedly engaging said clasp with one of the frame members, a torsional spring in said clasp adapted to normally press said clasp into operative position, said spring having one end fixed in the frame member, lugs integral with said clasp engaging in recesses in the frame member, said lugs limiting the rise of said clasp, an in-

clined catch plate formed with the bottom of said clasp, and a pair of lugs formed with the other of said frame members, said lugs having bevelled faces adapted to raise said 5 clasp by contact with the inclined catch plate and engage over the inner edge thereof when said frame members are closed.

This specification signed and witnessed this ninth day of April, 1921.

FRANZ A. FULLER.
